UNITED STATES PATENT OFFICE

DANIEL W. RICHARDS, OF ROANOKE, VIRGINIA

RAILWAY SIGNALING APPARATUS

Application filed April 9, 1931. Serial No. 528,865.

My invention relates to railway signaling apparatus.

I will describe certain forms of apparatus embodying my invention, and will then point out the novel features thereof in claims.

In the accompanying drawings, Fig. 1 is a view showing in vertical section, one form of relay embodying my invention, and Fig. 2 is a top plan view with top plate removed of the relay shown in Fig. 1. Fig. 3 is a sectional view showing the auxiliary contact mechanism forming part of the relay illustrated in Figs. 1 and 2. Fig. 4 is a diagrammatic view showing one form of railway signaling system embodying my invention and employing the relay illustrated in Figs. 1 and 2.

Similar reference characters refer to similar parts in all five views.

Referring first to Figs. 1 and 2, the reference character R designates a relay which, in the form here shown, comprises a base plate 1 and a top plate 2 spaced apart by glass sides 3. Attached to the base plate 1 are two upstanding posts 4 and 5 provided with trunnion screws 6 and 7, respectively, and mounted for rotation in these trunnion screws is a shaft 14 carrying a vane 8 of suitable electro-conductive material such as aluminum.

The vane 8 is controlled by a C-shaped laminated iron yoke or core 9 supported on, and secured to, bosses 10 which are formed integral with the base plate 1. The core 9 is provided with an energizing winding 11 constructed in two sections located on opposite sides, respectively, of the air gap in the core. These two winding sections are connected in series, and the leads 12 from the winding are, in turn, connected to two binding posts mounted on the top plate 2. Each pole of the core 9 is provided with the usual ferrule 46 of copper or other electro-conducting material (Fig. 1) partially enclosing the pole face to produce a shifting magnetic field when the winding is supplied with alternating current.

A pin gear 13, carried by the shaft 14, is

connected thereto by means of clutch mechanism 15, and this gear meshes with a segment gear 16. The clutch mechanism 15 may be of any suitable type and, as here shown, is similar to that described in Letters Patent of the United States, No. 1,627,322, granted to Robert M. Gilson on May 3rd, 1927, for electrical relays. The segment gear 16 is supported on, and is fastened to, a counter-shaft 17 which is journaled in trunnion screws 18 and 19 carried by posts 20 formed integral with the base plate 1. The four trunnion screws 6, 7, 18 and 19 are provided with lock nuts 6^a, 7^a, 18^a, and 19^a, respectively, to maintain them in permanent adjustment.

A crank 21 is also fixed to the counter-shaft 17 and to the segment gear 16, and this crank is formed with two lips 24 which are pivotally connected with the lower end of a link 25. The upper end of the link 25 is pivotally attached to the free end of a substantially horizontal arm 26 forming part of a contact carrying rocker 27. The contact carrying rocker 27 is mounted to swing in bearing screws 28 carried by brackets 29 which are fastened to the top plate 2, and the rocker is provided with a plurality of flexible contact fingers only two of which, 30 and 31 are shown in Fig. 1. These contact fingers cooperate with two fixed contacts 30^a and 31^a, respectively, to close a front contact 30—30^a or a back contact 31—31^a as will be explained hereinafter. The fixed contacts 30^a and 31^a are secured to the top plate 2 by means of terminal posts 30^b and 31^b, respectively.

Also formed on the crank 21 is a stud 22 into which is screwed a counter-weight rod 23. The counter-weight rod 23 is provided with two counter-weights 23^a which are adjustable on the rod, and which together with the segment gear 16 bias the crank 21, and hence the rocker 27, to the position in which the front contact 30—30^a is open and the back contact 31—31^a is closed, as shown in the drawings.

The relay also comprises auxiliary contact mechanism which, as best seen in Fig. 3, comprises two flexible contact fingers 34 and 35 mounted on an insulating block 36. The insulating block 36, in turn, is attached to a

framework A which is secured to the post 5 and one of the posts 20 by means of the trunnion screws 7 and 18 and their associated lock nuts 7^a and 18^a. Mounted in the framework A directly above the contact fingers 34 and 35 is a fixed bolt 37, and pivotally supported on this bolt is a crank 38. One arm 38^a of the crank 38 extends downwardly adjacent the contact fingers 34 and 35, and is provided with an insulating roller 45 which cooperates with the contact finger 34 to at times move this finger into engagement with the contact finger 35 to close a contact 34—35 as will be described hereinafter. The other arm 38^b of the crank 38 extends through the opening 16^c in the segment gear 16, and is adapted to cooperate with the radial arms 16^a and 16^b of the segment gear in a manner which will also be described hereinafter.

20 A metal washer 39 is fastened to the bolt 37 adjacent one side of the crank 38 by means of a cotter key 40, and interposed between this washer and the crank is a friction disc 41. A second friction disc 42 is also located 25 on the bolt 37 on the opposite side of the crank from the disc 41. The discs 41 and 42 are free to turn on the bolt 37, but the combination of the crank and friction discs is held in close contact with the fixed washer 39 by 30 the pressure exerted by a coil spring 44 on a metal washer 43 which is loosely mounted on the bolt 39 adjacent the disc 42, the spring 44 being supported on the bolt 39 between the frame and the washer 43 as best seen in Figs. 35 1 and 2.

The operation of the relay as a whole is as follows: When winding 11 is deenergized, no torque is exerted on the vane, and under these conditions, the segment gear 16 is held 40 in its lowermost position in which it is illustrated in the drawing, due to its own weight and to the combined weight of the counter-weight rod 23 and the counter-weights 23^a. When the segment gear occupies this position, back contact 31—31^a is closed and front contact 30—30^a is opened. Furthermore, when the segment gear occupies this position, the lower edge of the upper radial arm 16^a of the segment gear 16 engages the arm 38^b 45 of the crank 38 and holds this crank in the position in which it is illustrated in Fig. 3, so that contact 34—35 is open.

When alternating current of the proper value is supplied to winding 11, the vane 8 50 is rotated by induction motor action in a clockwise direction, as viewed in Fig. 1, thereby causing the pinion 13 to drive the segment gear 16 in a counter-clockwise direction. This motion, communicated to the rocker 27 opens the back contact 31—31^a 55 and closes the front contact 30—30^a. Furthermore, shortly before the segment gear 16 reaches the upper end of its stroke, the upper edge of the lower arm 16^b of the segment gear engages the arm 38^b of the crank 38.

38 and rotates this crank to a position in which the contact finger 34 is moved into engagement with the contact finger 35 by the insulating roller 45, thereby closing the contact 34—35. The motion of the segment gear after the front contact 30—30^a has become closed, and until the segment gear clip 16^d 70 engages the stop 32, causes the tip of the front contact finger 30 to slide upon the fixed contact member 30^a.

As long as the motor device remains energized, the parts are held in the positions just described against the torque exerted by the segment gear and by the counter-weights 23^a. When the motor device becomes deenergized, however, this torque acts to return the segment gear to its original position. As soon as the segment gear starts to return, the lower radial arm 16^b of the segment gear moves out of engagement with the arm 38^b 80 of the crank 38, but the crank continues to hold contact 34—35 closed under these conditions due to the friction between the crank, the friction discs and the fixed washer 39. About midway of the downward movement of the segment gear, front contact 30—30^a 85 opens and back contact 31—31^a closes, and when the segment gear has descended almost to its lowermost position, the upper radial arm 16^a of the segment gear engages the arm 38^b of the crank 38 and moves the crank to the position in which the roller 45 is out of engagement with the contact finger 34, thereby permitting contact 34—35 to open. When the segment gear reaches its lowermost position, the clip 16^d strikes the stop 33 thereby 90 preventing further movement of the segment gear. It will be seen that due to the inertia of the moving parts and the comparatively large distance the segment gear 16 must move before the front contact is opened and the back contact is closed, a considerable interval of time elapses after deenergization of winding 11 before this contact operation occurs. The duration of this time interval may be regulated by the size of the counter-weights 23^a and by their distance from the center of the shaft, which distance may be varied by screwing them up and down on the counter-weight rod 23. 95

100 It will be apparent, therefore, that with the relay constructed in the manner just described, when the relay becomes energized, the contact 34—35 does not become closed until after the back contact of the relay has become opened and the front contact has become closed; and that, when the relay becomes deenergized, the contact 34—35 remains closed until after the front contact has become opened and the back contact has become closed. It will be readily understood, therefore, that the contact 34—35 of this relay operates in the same manner with respect to the front and back contacts of the relay as the front contacts of a slow acting 105 110 115 120 125 130 135 140 145 150

relay would operate if the slow acting relay were controlled by the front contact of this relay, thereby enabling this relay to perform the same functions under certain conditions as have heretofore been performed by two relays.

Referring now to Fig. 4, the reference characters 46 and 46^a designate the track rails of a stretch of railway track over which traffic 10 normally moves in both directions. These track rails are divided by means of insulated joints *a* into a plurality of successive track sections, only two of which B—C and C—D are illustrated in the drawings. Track section 15 B—C is provided with a track circuit comprising a track relay R¹ connected across the rails adjacent the right-hand end of the section and a suitable source of current connected across the rails adjacent the left-hand 20 end of the section; and section C—D is provided with a similar track circuit comprising a track relay R² connected across the rails of the section adjacent the left-hand end of the section, and a source of track circuit current 25 connected across the rails adjacent the right-hand end of the section. As here shown, the source of track circuit current for each track section is a transformer T, the primary 47 of which is connected with the rails, and the 30 secondary 48 of which is supplied with current from the terminals X and Y of a suitable source not shown in the drawings. The track relays R¹ and R² are similar to the relay R previously described in connection with 35 Figs. 1, 2 and 3.

Located at point D is a signal F^D for governing westbound traffic over section C—D, that is to say, traffic moving from right to left over this section, and located at point C 40 is a similar signal F^C for governing westbound traffic over section B—C. The signals F^C and F^D, in the form here shown, are light signals, and each comprises two lamps G and R which indicate "proceed" and "stop", 45 respectively, when illuminated.

Signal F^D is controlled by a home relay H^D. When home relay H^D is energized, a circuit is completed for lamp G of this signal which passes from terminal X through front 50 contact 49—49^a of relay H^D, wire 50, and the filament of lamp G to terminal Y. When this circuit is closed, lamp G is lighted, and signal F^D therefore indicates proceed. When home relay H^D is deenergized, a circuit is then 55 completed for lamp R of signal F^D which circuit passes from terminal X through back contact 49—49^b of relay H^D, wire 62, and the filament of lamp R to terminal Y. When 60 this latter circuit is closed, lamp R is lighted and signal F^D therefore indicates stop. It will be apparent, therefore, that signal F^D will indicate proceed or stop according as relay H^D is energized or deenergized. Signal 65 F^C is controlled by a relay H^C in the same

manner as the signal F^D is controlled by relay H^D.

Relay H^D is provided with a pick-up circuit which passes from terminal X through front contact 51 of relay H^C, wire 52, front contact 30—30^a of track relay R², wire 53, and the winding of relay H^D to terminal Y. Relay H^D is also provided with another circuit which passes from terminal X through front contact 54 of a stick relay S, wires 55 and 52, front contact 30—30^a of track relay R², wire 53, and the winding of relay H^D to terminal Y. It will be apparent, therefore, that when track relay R² is deenergized relay H^D will be deenergized but that when relay R² is energized, relay H^D will be energized provided relay H^C or relay S is then energized.

Stick relay S is provided with a pick-up circuit which passes from terminal X through back contact 31—31^a of track relay R¹, wire 56, auxiliary contact 34—35 of relay R¹, wire 57, back contact 31—31^a of track relay R², and the winding of stick relay S to terminal Y. Relay S is also provided with a stick circuit which passes from terminal X through back contact 59 of relay H^C, wire 60, front contact 61 of relay S, wire 63, and the winding of relay S to terminal Y.

Relay H^C is controlled by front contact 30—30^a of relay R¹ and by traffic conditions to the left of point B in such manner that this relay will be energized except when track relay R¹ is deenergized, or when track relay R¹ is energized and the section to the left of section B—C is occupied by a train which is approaching section B—C.

As shown in the drawings, track sections B—C and C—D are both unoccupied. Track relays R¹ and R² are therefore both energized. Relays H^C and H^D are also energized and signals F^C and F^D therefore both indicate proceed. Stick relay S, however, is deenergized, the pick-up circuit for this relay being open at back contact 31—31^a of track relay R², and the stick circuit for this relay being open at both back contact 59 of relay H^C and at front contact 61 of relay S.

In explaining the operation of the signaling system shown in Fig. 4 as a whole, I will first assume that with the parts in the positions just described, a westbound train traverses the stretch of track shown in the drawings. When the train enters section C—D, track relay R² becomes deenergized and opens its front contact 30—30^a and closes its back contact 31—31^a. The opening of front contact 30—30^a interrupts both the pick-up and stick circuits for relay H^D, and relay H^D therefore becomes deenergized, thus causing signal F^D to indicate stop. When the train enters section B—C, track relay R¹ becomes deenergized. This, in turn, deenergizes relay H^C which causes signal F^C to also indicate stop. Furthermore, since relay R¹

is similar to the relay R previously described in connection with Figs. 1, 2 and 3, it will be apparent, that when relay R¹ becomes deenergized, there is a brief interval of time 5 during which its back contact 31-31^a and its auxiliary contact 34-35 are both closed, and during this interval of time, the pick-up circuit previously traced for stick relay S is closed at these contacts and at back contact 31-31^a of track relay R². Stick relay S therefore becomes energized and closes its front contacts. Since relay H^c is now deenergized, the closing of front contact 61 of stick relay S completes the stick circuit 10 for this relay, so that relay S will now remain energized even though track relay R² subsequently becomes energized due to the train having passed completely out of section C-D. As a result, when relay R² next 15 becomes energized under these conditions, it completes the circuit for relay H^p including front contact 54 of stick relay S, and relay H^p therefore becomes energized. This causes signal F^p to indicate proceed, thereby permitting a following train to enter section 20 C-D. When the train has passed completely out of section B-C, track relay R¹ becomes energized, and when the train has passed completely out of the section to the 25 left to point B, relay H^c becomes energized. The energization of relay H^c interrupts the stick circuit which was previously closed for relay S, and closes the circuit for relay H^p including front contact 51 of relay H^c. Stick 30 relay S therefore now becomes deenergized but relay H^p remains energized. Furthermore, the energization of relay H^c causes signal F^c to indicate proceed, thus restoring the parts to the conditions in which they are 35 illustrated in the drawings.

I will next assume that the section to the 40 left of section B-C is occupied by a train which is approaching section B-C, and that this train traverses the stretch of track illustrated in the drawings. Under these conditions, relay H^c will be deenergized as previously pointed out and signal F^c will therefore indicate stop. Furthermore, the one 45 circuit previously traced for relay H^p including front contact 51 of relay H^c will then be open at this contact and the other circuit for relay H^p will be open at front contact 50 54 of stick relay S, so that relay H^p will also be deenergized. Signal F^p will therefore 55 likewise indicate stop. When the train enters section B-C, relay R¹ becomes deenergized. This interrupts the circuit for relay H^c at the front contact 30-30^a of relay R¹, so that relay H^c will now remain deenergized 60 as long as section B-C is occupied. Furthermore, the deenergization of track relay R¹ causes contact 31-31^a of this relay to become momentarily closed while auxiliary contact 34-35 is still closed in the manner 65 previously described, but since track relay

R² is now energized, the pick-up circuit for relay S remains open at contact 31-31^a under these conditions, and stick relay S therefore remains deenergized. When the train 70 enters section C-D, track relay R² becomes deenergized. This interrupts both the pick-up and stick circuits for relay H^p, thus insuring that relay H^p will not become energized as long as section C-D is occupied. When the train passes out of section B-C, track relay R¹ again becomes energized. The closing of front contact 30-30^a of this 75 relay completes the circuit for relay H^c under these conditions, and relay H^c therefore also becomes energized, so that signal F^c now 80 indicates proceed. When the train passes out of section C-D, track relay R² becomes energized. Since relay H^c is then deenergized, the closing of front contact 30-30^a of track relay R² completes the circuit for relay H^p including front contact 51 of relay H^c, and relay H^p now picks up. This causes 85 signal F^p to indicate proceed. The parts are then restored to the positions in which they are 90 illustrated in the drawings.

Referring now to Fig. 5, as here shown, the rails 46 and 46^a of a stretch J of railway track over which traffic moves at times in both directions are divided by means of insulated joints a, to form two track sections 95 K-L and L-M. Section K-L is connected with a siding N by means of a switch P which is moved to normal and reverse positions by suitable operating mechanism forming no part of my invention, and therefore not shown in the drawings. Operatively connected with the switch P is a circuit controller V, comprising a contact 63-63^a which is closed when and only when the switch P occupies its normal position in 100 which it is illustrated in the drawings.

The track sections K-L and L-M are each provided with the usual track circuit comprising, in the form here shown, the primary 47 of transformer T connected across the rails at one end of the section and a track relay Q connected across the rails at the other end of the section, the track relays for the two sections being designated Q¹ and Q², respectively. 105

Intersecting the stretch J at or near the junction of the sections K-L and L-M is a highway Z, and located at this intersection is a highway crossing signal W which, in the form here shown, is an electric bell. 110

The bell W is controlled by an interlocking relay U which may be of any suitable type, such for example, as the relay illustrated in United States Letters Patent No. 799452, granted to W. W. Coleman on Sept. 12, 1905. As here shown, the relay U comprises two magnets 64 and 65 which control two back contacts 66 and 67, respectively. If magnet 64 becomes deenergized before magnet 65, back contact 66 will become closed, 115

but if magnet 64 becomes deenergized subsequent to magnet 65, the interlocking mechanism will prevent back contact 66 from becoming closed. Similarly, if magnet 65 becomes deenergized before magnet 64, back contact 67 will become closed, but if magnet 65 becomes deenergized subsequent to magnet 64, the interlocking mechanism will prevent back contact 67 from becoming closed.

When contact 66 of relay U is closed, a circuit is completed for bell W which passes from terminal X through contact 66 of relay U and the operating mechanism of bell W to terminal Y. Similarly, when contact 67 of relay U is closed, another circuit is completed for bell W which passes from terminal X through contact 67 of relay U and the operating mechanism of bell W to terminal Y. When either of these circuits is closed bell W will operate, thereby warning users of the highway that a train is approaching along the railway.

Interlocking relay U, in turn, is controlled by the track relays Q¹ and Q², and by a relay R³ which is similar to the relay R described in connection with Figs. 1, 2 and 3. Magnet 65 of relay U is provided with a circuit which passes from terminal X through front contact 68 of relay Q² and the winding of magnet 65 to terminal Y. Magnet 64 of relay U is similarly provided with a circuit which passes from terminal X through wire 69, front contact 70 of relay Q¹, wire 71, the winding of magnet 64, and wire 72 to terminal Y. Magnet 64 is also provided with another circuit which passes from terminal X through back contact 31-31^a of relay R³, auxiliary contact 34-35 of relay R³, wires 73 and 71, the winding of magnet 64, and wire 72 to terminal Y.

Relay R³ is controlled by contact 63-63^a of circuit controller V, the circuit for this relay passing from terminal X through contact 63-63^a of circuit controller V, wire 74, and the winding of relay R³ to terminal Y. It will be apparent therefore that this relay will be energized when switch P occupies its normal position but that this relay will become deenergized when the switch is moved to its reverse position.

As shown in the drawings, sections K-L and L-M are both unoccupied so that track relays Q¹ and Q² are both energized. The circuit for magnet 65 of relay U is therefore closed at front contact 68 of relay Q², and the one circuit for magnet 64 is likewise closed at front contact 70 of relay Q¹, so that both magnets 64 and 65 of interlocking relay U are energized. Both circuits for bell W are therefore open, and bell W is accordingly deenergized. Switch P occupies its normal position, and the circuit for relay R³ is therefore closed, so that relay R³ is energized.

I will now assume that a train moving

causes track relay Q² to become deenergized which in turn deenergizes magnet 65 of interlocking relay U. Back contact 67 of relay U therefore becomes closed and completes the circuit for bell W including this contact, so that bell W starts to operate. When the train enters section K-L, relay Q¹ becomes deenergized and deenergizes magnet 64 of relay U. Contact 66, however remains open under these conditions due to the interlocking mechanism of the relay. When the train has passed completely out of section L-M, relay Q² again becomes energized, thereby energizing magnet 65 and hence opening back contact 67. This interrupts the circuit which was previously closed for bell W at this contact, and bell W therefore stops operating. When the train has passed completely out of section K-L, relay Q¹ again becomes energized. This energizes magnet 64, and the parts are then restored to the positions shown.

When a train moving from left to right traverses the stretch of track J, the operation of the apparatus will be exactly the reverse of that just described, and will be readily understood from an inspection of the drawings without tracing the sequence of operation in detail.

I will next assume that it is desired to permit a train in siding N to traverse stretch J from left to right after another train which is moving from right to left has passed switch P but is still in section K-L. Under these conditions, relay Q² and magnet 65 will of course be energized, but relay Q¹ and magnet 64 will be deenergized. Furthermore, since magnet 64 became deenergized after magnet 65, contact 66 will be held open by the interlocking mechanism of relay U, so that signal W will be silent. Relay R³ will be energized. In order to permit the train to enter stretch J, switch P must be reversed. When this is done, contact 63-63^a of circuit controller V is opened and relay R³ therefore becomes deenergized. When relay R³ becomes deenergized, there is a brief interval of time after back contact 31-31^a becomes closed before auxiliary contact 34-35 becomes opened, and during this interval of time the circuit for magnet 64 of relay U including these contacts is closed. Magnet 64 therefore becomes energized for a sufficient interval of time to release the interlocking mechanism of relay U with the result that when magnet 64 subsequently again becomes deenergized due to the opening of contact 34-35, back contact 66 of relay U becomes closed. This completes the circuit for bell W including this contact and bell W starts to operate, thereby warning the users of the highway that a train is approaching on the railway. When the train enters section L-M, relay Q² becomes deenergized and deenergizes magnet 65 of interlocking

relay U. Contact 67 remains open, however, under these conditions. When both trains have passed completely out of section K—L, track relay Q¹ picks up and closes the circuit for magnet 64 including front contact 70 of relay Q². Magnet 64 therefore becomes energized, thus opening contact 66 and hence stopping the operation of bell W. When the train which entered stretch J from the siding N has passed completely out of section L—M, relay Q² picks up and energizes magnet 65. The parts are then restored to the positions which they normally occupy when switch P is in its reverse position and sections K—L and L—M are both unoccupied.

Although I have herein shown and described only a few forms of railway signaling apparatus embodying my invention, it is understood that various changes and modifications may be made therein within the scope of the appended claims, without departing from the spirit and scope of my invention.

Having thus described my invention, what I claim is:

1. In combination, two adjacent sections of railway track, a track circuit for each track section including a track relay, one of said track relays being provided in addition to the usual front and back contacts with an auxiliary contact which becomes closed after the back contacts of the relay have become opened when the relay becomes energized and which subsequently remains closed when the relay becomes deenergized until after the back contacts have become closed, a third relay controlled in part by said one track relay, a stick relay, a pick-up circuit for said stick relay including said auxiliary contact and a front contact of said one track relay as well as a back contact of the other track relay, a stick circuit for said stick relay including a back contact of said third relay and a front contact of said stick relay; a fourth relay controlled by said other track relay, said stick relay and said third relay; and signals for governing traffic over said two sections controlled by said third and fourth relays.

2. In combination, two adjacent sections of railway track, a track circuit for each track section including a track relay, one of said track relays being provided in addition to the usual front and back contacts with an auxiliary contact which becomes closed after the front contacts of the relay have become closed when the relay becomes energized and which subsequently remains closed when the relay becomes deenergized until after the back contacts have become closed, a third relay controlled in part by a front contact of said one track relay, a stick relay, a pick-up circuit for said stick relay including said auxiliary contact and a back contact of said

one track relay as well as a back contact of the other track relay, a stick circuit for said stick relay including a back contact of said third relay and a front contact of said stick relay; a fourth relay, a first circuit for said fourth relay including a front contact of said other track relay and a front contact of said third relay, a second circuit for said fourth relay including a front contact of said other relay and a front contact of said stick relay; a first signal for governing traffic in one direction over the section with which said one track relay is associated controlled by said third relay, and a second signal for governing traffic over the other section in the same direction as said first signal governed by said fourth relay.

In testimony whereof I affix my signature.

DANIEL W. RICHARDS.
